UNITED STATES PATENT OFFICE.

EDGAR M. DENNISTON, OF BURLINGTON, IOWA.

ROOF HOOK.

Application filed January 2, 1925. Serial No. 150.

To all whom it may concern:

Be it known that I, EDGAR M. DENNISTON, a citizen of the United States, and a resident of Burlington, in the county of Des Moines and State of Iowa, have made a certain new and useful Invention in Roof Hooks; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a side view of the invention as applied.

Figure 2 is a similar view on a larger scale showing a different adjustment.

20 Figure 3 is an end view of the invention.

Figure 4 is a side view of the invention folded.

Figure 5 is a side view of the invention showing another adjustment.

25 Figure 6 is an end view of the same.

Figure 7 is a side view of the same folded.

Figure 8 is a perspective view of another form of the invention as applied.

30 Figure 9 is a side view of the same on a larger scale.

Figure 10 is a side view of the same folded.

Figure 11 is an edge view of the same.

Figure 12 is a plan view of the form of the invention shown in Figure 9.

35 Figure 13 is a fragmentary detail side view of the same.

Figure 14 is a side view of another modification of the invention.

40 Figure 15 is a side view of another modification.

The invention has relation to roof hooks, for painters and others working upon the sides of buildings, and used for the attachment of hoisting ropes for the platforms upon which the workmen are supported, the object being to provide an improved device for this purpose.

45 The invention consists in the novel construction and combinations of parts, as hereinafter set forth.

In the accompanying drawings illustrating the invention, the numeral 2 designates the workmen's platform and 3 the hoisting ropes

at one end of said platform and operating in conjunction with the block and tackle 4. 55

In Figures 1 to 7 inclusive of these drawings the roof hook is shown as formed with upper and lower parallel arms or sections 5 and 6, and a vertical connecting arm or section 7, the upper arm having at its inner free end the hook 8, and the lower arm having at its inner free end the pulley block 4', the vertical connecting arm 7 being located at the outer ends of said upper and lower arms out of the way of the building cornice or other projection. 60

The sections or arms 5, 6, and 7 are made of light steel bars, it being preferred that the arms shall be foldable to enable the device to be carried around more easily, and to this end said arms are pivotally connected at 9 and 10, corner stops formed of lugs bent integrally of the metal of the arms being shown at 11, and serving to limit the opening movement of the arms from folded position. 75

The lugs 11 are preferably bent outwardly in opposite directions and the upper and lower arms 5 and 6 are located upon opposite sides of the upright arm 7, as best shown in Figure 2 to facilitate the folding of the device, the three arms or bars being in this way foldable into compact parallel relation for placing in a tool box or vehicle. 80

In order to make the device of the proper strength to bear the loads to which it is subjected, a slideable upright tie bar 14 is slid over the ends of the upper and lower arms 5 and 6 with the upper and lower oppositely bent or looped ends 15 thereof engaging said upper and lower arms, said tie bar being preferably of double curved form, in order to avoid contact with the building cornice or other projection. The tie bar is slid towards the vertical wall of the building as near as possible in order to transmit the strain of the load from the hook 8 to the block and tackle suspension device for the workmen's platform as directly as possible, the strain of the load being transmitted from the hook 8 through the tie bar to said block and tackle, with no strain upon the upright arm 7 of the device. The tie bar 14 has bolts 14' connecting the branches of the upper and lower looped ends thereof, said bolts contacting with the inner longitudinal edges. 95

100

105

of the upper and lower arms 5 and 6 to resist folding of the same upon the pivots 9 and 10.

In using the device upon a building having no cornice, in which case it is necessary to extend the hook 8 beyond the vertical wall of the building, the lower arm or bar 6 may be set back or adjusted suitably to admit of the desired extension of the said hook of the upper arm, this being provided for by a horizontal series of perforations 10' in the lower arm or bar 6, with any one of which the bolt 10 is adapted to engage. In this case, the workmen's platform is suspended from a slid able hook 16 engaging the lower bar 6 and adjusted to proper position thereon.

In this case also, the lower arm or bar 6, which is preferably provided with a downturned inner or hooked free end 6', will bear against the vertical wall of the building, as best shown in Figure 1 or may do so, the block and tackle being suspended from an eye of the hook 6'.

The upper arm or bar 5 is provided with a horizontal series of perforations 9' engageable by the pivot bolt 9 in adjusting the effective length thereof.

In case it is desired to shorten the effective lengths of the arm 7 and of the tie bar 14, as best shown in Figure 5, the upper and lower arms 5 and 6 are changed over to the sides of the upright arm 7 opposite to the sides thereof upon which they are normally located, and the arm 7 is provided at its upper and lower ends each with two perforations 7' with the inner of which the bolts 9 and 10 are engaged (said bolts being normally engaged with the outer of said perforations) and the tie bar 14 is provided at its upper and lower looped ends 15 each with two perforations 15', with the inner of which the bolts 14' are engaged (said bolts being normally engaged with the outer of said perforations). Lug bolts 17 project laterally of the arm 7 upon opposite sides thereof, being engaged by the arms 5 and 6 to limit the outer or unfolding movement thereof. The lug bolt 17 at the upper end of the arm 7 projects laterally oppositely to the projection of the upper bent lug 11, and the lug bolt 17 at the lower end of the arm 7 projects laterally oppositely to the projection of the lower bent lug 11, in order to enable the upper and lower arms 5 and 6 to be folded in the normal location thereof shown in Figure 2.

A modification of the invention is shown in Figures 8 to 13 inclusive wherein similar parts are characterized by the same reference numerals differentiated by the exponent "x". In this modification the hook proper 8' is riveted to the upper arm of the device, the tie bar 14' and the upper and lower arms 5 and 6 are not adjustable, and the corner stops 11' are structurally different, and the

downturned inner hooked free end of the lower bar 6' is lacking.

Another modification is shown in Figure 14 wherein similar parts have similar reference characters differentiated by the exponent "y", and wherein corner braces 12 connecting the arms 5, 6, and 7 are detachable therefrom by the removal of the connection bolts 13.

Another modification is shown in Figure 15 wherein similar parts have similar reference characters differentiated by the exponent "z", except that the eye at the lower side of the device has the reference character 6'', and wherein the device is bent up into form from rod metal, the tie bar 14'' when slid inwardly adding the necessary strength.

I claim:

1. A roof hook having upper and lower parallel arms, an upright connecting arm at the outer end thereof, and a tie bar connecting said upper and lower arms intermediately of the length thereof and acting to transmit the strain of the load more directly and to relieve said connecting arm of strain.

2. A roof hook having upper and lower parallel arms, an upright connecting arm at the outer end thereof, and a tie bar connecting said upper and lower arms intermediately of the length thereof and adjustable thereon.

3. A roof hook, having upper and lower parallel arms, an upright connecting arm at the outer end thereof, and a tie bar connecting said upper and lower arms intermediately of the length thereof and of double curved form.

4. A roof hook having upper and lower parallel arms, an upright connecting arm at the outer end thereof, and a tie bar connecting said upper and lower arms intermediately of the length thereof, said upper and lower arms and the connecting arm being pivotally connected and foldable into compact form and said tie bar being detachable therefrom.

5. A roof hook having upper and lower parallel arms, an upright connecting arm at the outer end thereof, and a tie bar connecting said upper and lower arms intermediately of the length thereof, said upper and lower and connecting arms being pivotally connected and foldable into compact form and said tie bar being detachable therefrom, the upper and lower arms being disposed upon opposite sides of said connecting arm, and the latter having stops projecting oppositely laterally thereof to limit the unfolding movement of the upper and lower arms and facilitating the folding of the device.

6. A roof hook having upper and lower parallel arms; an upright connecting arm at the outer end thereof, and a tie bar connect-

ing said upper and lower arms intermediately of the length thereof, the connection of the upper and lower arms with the connecting arm being adjustable to adjust the effective height of the device, and the tie bar having adjustable connection with the upper and lower arms for the same purpose.

7. A roof hook having upper and lower parallel arms, an upright connecting arm at the outer end thereof, and a tie bar connecting said upper and lower arms intermediately of the length thereof, the connection of the upper and lower arms with the connecting arm being adjustable to adjust the effective height of the device and the effective

length thereof, the tie bar having adjustable connection with the upper and lower arms.

8. A roof hook having upper and lower parallel arms, an upright connecting arm at the outer end thereof, and a tie bar connecting said upper and lower arms intermediately of the length thereof, the connection of said lower arm with the connecting arm being adjustable to shorten the effective length of the lower arm, and an adjustable suspension device upon said lower arm.

In testimony whereof I affix my signature.

EDGAR M. DENNISTON.
